Design

Charles H. Clayton
Copying Press Stand
Patented March 23, 1858.

Dec. 994

Charles H. Clayton, of New York, N. Y.
Letters Patent No. 994, - Dated Mar. 23, 1858

The schedule referred to in these Letters Patent & making part of the same.

To all whom it may concern:

Be it known that I, Charles H. Clayton, of New York, in the County and State of New York, have invented a new and original design for the sides or feet of Copying Press stands, or similar purposes, and I do hereby declare that the following is a full and exact description of the same.

The general plan of my design is that of a Harp or vase, surmounted by a rectangular piece, and resting on a shallower rectangular base, which latter in its turn rests on a wider and broader foot, whose under side is scolloped out, where the same does not rest upon the floor. The interior of the Harp figures (A. A.) contains at the top a crescent or shell (B) with its hollow side downwards. Below this are introduced two figures (C. C.), each the reverse of the other, rectilinear towards the middle.

Dec. 994

and curved in opposite directions at the ends. All these internal figures are in contact with each other, and delicately support and stiffen the structure. The lower sides of the last described figures (C.C) rest on, or are joined to the scroll like convolution formed by the continuation within the harp or vase shaped figure of the strips or S shaped bands which form its gracefully curved outlines. (m. m. m. m.) are characteristic scrolls, which serve to unite and strengthen the parts at the points represented. The whole figures are formed of bands which are thickened at the edges, either by flat rectangular or by semi-circular strips.

My design is correctly represented in every detail in the accompanying drawing.

What I claim as my design and desire to secure by Letters Patent, is the within described Press Stand foot consisting of the harp or vase shaped figure formed by the two reverse curved bands A.A. with the shell B. the two figures C.C. and the joining scrolls (m. m. m. m.) all supporting, and connected with each other and forming one harmonious design as represented.
